UNITED STATES PATENT OFFICE.

THOMAS G. ROEBUCK, OF JERSEY CITY, NEW JERSEY.

IMPLEMENT FOR MAKING COVERED BUTTONS.

SPECIFICATION forming part of Letters Patent No. 355,030, dated December 23, 1886.

Application filed September 9, 1886. Serial No. 213,156. (No model.)

To all whom it may concern:

Be it known that I, THOMAS G. ROEBUCK, a citizen of the United States, residing at Jersey City, county of Hudson, and State of New Jersey, have invented certain new and useful Improvements in Implements for Making Covered Buttons, fully described and represented in the following specification and the accompanying drawings, forming a part of the same.

This invention relates to a tool or implement for the manufacture of what are known as "covered buttons." These buttons, as is well known, are composed of an interior mold or body formed of some rigid material, which is covered with any suitable fabric to form the outside of the button, the fabric being retained on the mold either by having its edges brought together at the back and fastened by sewing, as in the cheaper class of buttons, or by a metal retaining-ring, which, after the edges of the fabric are brought together at the back of the mold, is pressed onto the edges so as to hold them, and is secured in that position by some suitable means, usually by turning outward the edges of an eyelet extending from the back of the mold. Where these covered buttons are to be produced in large quantities, the operation is not particularly difficult or expensive; but it frequently happens that a person ordering a suit of clothes or a dress desires to have the buttons thereof covered with the same material of which the garment is made. When such orders are given, it has heretofore been necessary for the tailor or dress-maker to send pieces of the goods with which the buttons were to be covered to a button-manufacturer and have a sufficient number of buttons covered with that material to fill the special order. This of course occasioned considerable trouble and delay, and, aside from that, made the buttons comparatively expensive. It is highly desirable, therefore, to provide a means by which any tailor or dress-maker can readily produce covered buttons in small quantities, to fill any special orders that may be received, without the necessity of sending to a manufacturer of buttons for that purpose.

The present invention relates to a tool or implement which is especially adapted for this purpose.

As an understanding of the invention can be best given by an illustration and description

of the construction and operation of the tool or implement in which it is embodied, such description will now be given, reference being had to the accompanying drawings, in which—

Figures 1 to 5, inclusive, are views showing the several parts of the implement detached from each other. Fig. 6 is an enlarged view, partly in section, illustrating the first step in the operation of producing a covered button by the use of this implement. Fig. 7 is a similar view illustrating the next step in the operation of producing the button. Fig. 8 is a similar view illustrating the third or final step in the operation; and Fig. 9 is a still more enlarged view of a part of Fig. 8, the button-cover and the retaining-ring being shown in section in this view.

Referring to said figures, it will be seen that the tool or implement consists, essentially, of five parts—namely, an anvil, *a*, upon which the button rests during the covering operation, a tubular guide, *b*, which folds and holds the covering material around the edge of the mold, an annular crimper or gatherer, *c*, which crimps or gathers the material inward at the back of the mold, and an eyeleting head or punch, *d*, which opens the eyelet so as to hold the retaining-ring in position on the back of the mold, and a tubular cap or guide, *e*, in which the eyeleting-punch works. The anvil *a*, which is slightly concave at its top, so as to conform to the slightly-convex back of the mold, is secured to a base, *10*, of suitable size and shape to be conveniently grasped by the hand and to support the implement in an upright position when it rests upon a table or other support. The tubular guide *b* is of such size as to just slide freely over the anvil *a*, and is provided near its lower end with interior screw-threads, which engage with corresponding threads, *2*, formed on the outside of the anvil near its bottom, by which means the guide *b* can be adjusted to different positions, so as to project a greater or less distance above the end of the anvil. The crimper *c* is of annular form, and is provided with a downwardly-extending flange, *3*, which is adapted to just fit over the outside of the top of the guide *b*. The opening through the crimper is contracted above the flange *3*, so as to form an inclined shoulder, *4*, as clearly shown, the pur-

pose of which will appear when the operation of the implement is described. The cap *e* is made of sufficient size to fit over the crimpler *c*, and extend downwardly around the upper 5 end of the guide *b*, and is provided at its lower edge and upon opposite sides with bayonet-joints 5, which engage with studs 6, projecting from the upper end of the guide *b* in such manner as to lock the cap *e* to the guide. The 10 top of the cap *e* is tapped to receive the screw-threaded shank of the eyeleting-punch *d*. The lower end of the punch *d* is made concave, and it is tapered at its point, as shown at 7, so as to spread the end of the eyelet in the usual 15 manner when it is forced into the same.

The operation of the implement thus constructed is as follows: The guide *b* having been placed over the anvil *a* and screwed onto the threads 2 until its upper end is adjusted to the 20 proper height above the end of the anvil, as indicated in Fig. 6, a piece of fabric, 8, of suitable size to cover the button, will be placed over the end of the tubular guide *b*. The button-mold 11, of the ordinary form, which can 25 be found in the market, and which is provided at its back with a tubular eyelet, 9, through which projects the flexible tuft 1, is then placed on the fabric 8 and forced downward into the end of the guide *b* and onto the top of the an- 30 vil, as shown in Fig. 6. During this operation the edges of the fabric 8 will be turned upward around the edges of the mold, and be brought into position to be gathered or crimped inward onto the back of the mold preparatory to being 35 secured in position by the metal retaining-ring. The crimpler *c* will then be placed over the end of the guide *b*, as shown in Fig. 7, and the guide *b* will be run downward on the threads 2. During this operation the crimpler *c* will 40 be carried downward past the upwardly-projecting edges of the fabric 8, and the edges of the fabric, coming into contact with the inclined shoulder 4 of the crimpler, will be turned inward, as shown. The metal retaining-ring 12, 45 of the ordinary form, will then be inserted into the opening in the crimpler *c*, so as to overlie the edges of the fabric 8. The cap *e* will then be placed over the crimpler, and secured to the upper end of the guide *b* by means of the bayonet-joints 5 and lugs 6, and the eyeleting-punch *d* will be screwed downward until its tapered end 7 enters the end of the eyelet 9, as 50 shown in Figs. 8 and 9, and this movement of the punch being continued the eyelet will be spread so as to fasten the retaining-ring in position and secure the fabric around the mold, as shown in Fig. 9, thus completing the covered button. The eyeleting-punch will then be turned in the reverse direction, so as to 55 back it away from the button, and the cap *e* 60

and the crimpler *c* will be removed, thereby permitting the removal of the completed button from the implement.

It will be seen that by this means a simple and inexpensive implement is provided by 65 which tailors and others can readily manufacture such small quantities of covered buttons as may be required to fill special orders without the necessity of sending such orders to regular button-manufacturers to be filled.

It will of course be seen that the implements 70 may be manufactured in different sizes, so that each shop can be provided with two or three of the implements—one, for example, of suitable size for covering vest-buttons, another of suitable size for covering coat-buttons, and 75 another of larger size for covering overcoat-buttons, and other large buttons.

Although, as shown in the present case, the crimpler *c* is arranged to fit loosely on the upper end of the guide *b*, the flange 3 of the 80 crimpler can, if desired, be screw-threaded upon its interior and arranged to engage with corresponding threads formed on the upper end of the guide *b*, so that the crimpler can be screwed onto the upper end of the guide, instead of fitting loosely thereon, and this in 85 some cases may be found preferable.

What I claim is—

1. The combination, with the anvil *a* and tubular guide *b*, of the crimpler *c*, cap *e*, and 90 eyeleting-punch *d*, substantially as described.

2. In an implement for covering button-molds, the combination, with the anvil *a* and tubular guide *b*, movable upon the anvil, of the crimpler *c*, having the inclined shoulder 4, 95 substantially as described.

3. In an implement for covering button-molds, the combination, with devices for holding the mold and the fabric, of the crimpler *c*, provided with the inclined shoulder 4, arranged to crimp or turn the edges of the fabric inward over the back of the mold into position to be caught by the retaining-ring, substantially as described.

4. The combination, with the anvil *a*, of 105 the tubular guide *b*, adjustable thereon, the crimpler *c*, having the opening for the passage of the retaining-ring 12, the cap *e*, arranged to fit over and be secured to the guide *b*, and the eyeleting-punch *d*, screw-threaded and passing through an opening in the top of the cap, substantially as described.

In testimony whereof I have hereunto set my hand in the presence of two subscribing witnesses.

THOMAS G. ROEBUCK,
